BREECH CLOSURE AND FIRING MECHANISM

Joseph C. White, Wakefield, Mass., assignor to
White Automatic Gun Corporation, Portland,
Maine, a corporation of Maine

Original application November 23, 1931, Serial
No. 576,666. Divided and this application
April 29, 1933, Serial No. 668,587

4 Claims. (Cl. 42—3)

My present invention relates to guns and more particularly to a breech closure and firing mechanism for rifles, especially military rifles, and aims to provide improved and simplified mechanism for the purpose set forth.

This application is a division of my co-pending application Serial No. 576,666, filed November 23, 1931, now Patent No. 1,907,163, dated May 2, 1933.

10 In the drawing, illustrating, by way of example, one embodiment of the invention.

Fig. 1 is a vertical longitudinal section through the receiver and breech mechanism, the breech being closed and the firing pin cocked;

15 Fig. 2 is a similar view as in Fig. 1 but with the parts in fired position and the breech open;

Fig. 3 is a horizontal section taken substantially in the plane of the axis of the bore, with the parts in the position as in Fig. 1; and

20 Fig. 4 illustrates the firing pin actuating assembly, partly in side elevation and partly in vertical section, and upon a larger scale.

This divisional application being concerned primarily with the breech closure and firing mechanism, I have here illustrated only sufficient of the other parts of the gun to afford adequate understanding of the invention. Similar reference characters are used as in my above mentioned copending application, and parts not shown or referred to may be the same as in said co-pending application.

The rear portion of the barrel is indicated at 1, it being secured in the receiver or frame 2 as by means of the threaded connection as indicated at 9 and a set screw 10. The main side walls of the receiver 2 are seen in full length in Fig. 3. Other portions of the receiver appearing in Figs. 1 and 2 include the upper intermediate cross or bridge portion 68 and a rear cross portion 2*, seen at the lower left part of Figs. 1 and 2, and in plan in Fig. 3. A portion of the rear stock is seen at 4, Figs. 1 and 2, in which are mounted adjacent portions of the trigger frame 135, the latter including a rear post 137 and a depending foot 162.

While the present invention, in certain of its aspects, is applicable to guns of various types, it is illustrated in connection with a gas-operated gun, the rear portion of the gas-operated spring-returned action slide, actuator, or gas fork, being illustrated at 41. Longitudinal movement of the action slide 41, rearward, under the influence of the gas, serves to unlock and open the breech mechanism, and to retract the firing pin relatively to the breech block or bolt, while return

forward movement of the actuator, under influence of its return spring serves to close and lock the breech.

The breech closure includes a breech block or bolt indicated as a whole by the numeral 60. It is illustrated as a substantially symmetrical elongated rectangular element, having an approximately axial bore 111 for reception of the firing pin 61. It is associated with the action slide 41 in such manner that at certain times it travels with the slide while at other times the slide is permitted to move relatively to the block. The block is provided with a plurality of locking lugs, two of which are seen at 70, 70 in Fig. 3.

For locking the block in breech closing position, or releasing the same, I have provided a transversely, and herein vertically, movable lock 71, of general U-form as viewed in plan. The lock 71 is positioned in the forward portion of the receiver 2 wherein it is transversely or vertically movable but is retained against movement lengthwise the receiver. The lock 71 is provided with lateral locking ribs 72, 72, Fig. 3, slidably received in corresponding locking grooves 13, 13 in the side walls of the receiver 2. At the upper fore portion of the lock, at the base of the U, is a forwardly projecting shoulder 74 adapted to seat in a correspondingly shaped ledge at the fore part of the receiver. As best seen in Fig. 2 the lock 71 is provided internally with locking members 77, 77 which come into longitudinal alignment, in the closed and locked position of the breech, behind the corresponding lugs 70 on the block. Suitable cam connections, including the cam formations 84 in the action slide 41, are provided intermediate the lock and the slide for effecting the transverse vertical locking and unlocking movements of the lock 71.

To effect the desired locking and unlocking movements of the lock, it will be understood that a relative movement takes place between the action slide 41 and the block proper at the beginning of the rearward or recoil action and again at the close of the return forward or counter recoil action. Accordingly I have provided a releasable operative connection between the slide 41 and the block 60. Such connection herein includes a latch, action-connecting element or action plate 90, of general yoke-shape, straddling and seating on the block and guided in recesses therein for transverse, vertical movement relative to the block. In its down position, as in Fig. 2, the top or cross portion of said latch 90 is received in a cross recess 91, see Fig. 1, in the upper face of the block. The latch may be fur-

ther positioned by a downwardly projecting pin 92 adapted to extend through an aperture 93, into the bore of the block and into a longitudinal slot 124 in the top wall of the firing pin 61. This pin and slot arrangement aids in guiding and centering the firing pin and preventing turning thereof, and also serves as a safety feature to prevent premature firing of a cartridge if for any reason the breech block should not be completely closed and locked. Under the latter conditions the latch 90 would be down, as in Fig. 2, its pin 92 then preventing full advance of the firing pin, by engagement with the rear end of the slot 124 in the latter.

15 The depending arms of the latch 90 have at their lower portions lateral projections 94 co-operable with notches 97 in the action slide 41 for operatively engaging and disengaging the block and slide. When the latch 90 is in down position, as in Fig. 2, the action slide and block are operatively connected for movement together; when the latch 90 is elevated as in Fig. 1, being then lifted out of the notches 97 of the slide, the block is disconnected from the slide, permitting the latter to move relatively to the block.

20 25 The breech block or bolt 60 is equipped with an extractor 105 and an extractor spring 107 illustrated as a leaf spring lying along the upper face of the fore part of the block, but which may be otherwise formed.

30 35 The firing pin 61 previously referred to, and receivable in the bore 111 of the block, is itself an elongated hollow member having a nose 112 for detonating the cartridge primer. At its rear portion the firing pin is provided with a laterally extending head portion 113, externally of the block end of a configuration conforming generally to a cross-section of the latter, said head portion 113 preferably including lateral extensions 113a, 113b, Figs. 2 and 3, by which it is guided in the ways 65 of the receiver, which ways also slidably receive corresponding ribs on the breech block. Said head portion 113 of the firing pin also includes depending parts 113c, one at each side, in alignment with the two forks of the action slide 41, on which are provided lugs 62, Figs. 1 and 2.

40 45 The rear faces of said lugs are adapted to engage said depending portions 113b of the firing pin head 113, thereby to retract the firing pin within and relatively to the block, in connection with the block unlocking and opening movement of the actuator or slide 41, into sheathed position as illustrated in Fig. 2. An intermediate lower portion of the firing pin head 113 is adapted to be engaged behind the U-shaped spring nose 140 of the sear 138, as illustrated in Fig. 1, to hold the firing pin cocked. The sear is pivotally supported on the front portion of the trigger frame 135 as at 139.

50 55 60 The firing pin is provided with an actuating assembly, seen in Figs. 1 and 2 and in detail in Fig. 4. Said firing pin actuating means or spring assembly herein comprises a two-part coil spring, 65 including the forward spring 114 adapted to bear between the front wall of the firing pin 61 and a collar 115 on a floating sleeve 116. The rear section 123 of the spring also surrounds said sleeve, rearwardly of said collar 115, and said sleeve 116 is removably received on and retained by an elongated stationary stud 117, in the manner best seen in Fig. 4. The front end of said stud 117 is threaded as at 118 for passage through a corresponding threaded aperture 116a in the 70 75 rear wall of the sleeve 116. Said threaded means

retains the sleeve and stud against longitudinal bodily separation, when the parts are disassembled, without intentional unscrewing of the sleeve from the stud.

5 The stud 117 is mounted on and projects forwardly from an arm 119 of a supporting element or plate 120 adapted to be held in fixed position on the receiver, against the pressure of said two-part firing pin spring 114, 123. Said supporting element or plate 120 is constructed and arranged 10 for easy demounting, together with the firing pin and its actuating parts. It seats on the rear cross portion 2a of the receiver 2, being provided at its front portion with a pair of depending hooks 121. These hooks are engageable over the 15 front edge of said receiver portion 2a, thus releasably anchoring the plate 120 in position thereon. The plate 120 is further positioned and guided for forward, releasing movement, as by a pin 122 projecting up from the receiver cross 20 portion 2a and received in a longitudinal recess or guideway 122a in the under face of the plate 120.

25 After removal of the receiver cap 125, to be described, the entire firing pin assembly is readily 30 dismountable. The rearwardly extending portion of said plate is constituted as a thumb piece 120a. On pushing the plate 120 forwardly and tilting it, through the medium of its thumb piece 120a, the hooked portions 121 are disengaged from 35 the receiver portion 2a, whereupon the entire firing pin assembly may be withdrawn from the gun.

40 In said demounted condition of the firing pin and its operating parts, the two springs 114 and 123 normally remain upon the sleeve 116. The rear portion 123 of the two-part firing pin spring, surrounding the stud 117 and the rear portion of the sleeve 116, bears between the collar 115 of the latter and the arm 119 of the plate 120. 45 The sleeve and stud remain assembled, being prevented from bodily separation, longitudinally, by interengagement of the threaded portions 118, 116a, but they may readily be completely disengaged, when desired, by turning the threaded portion 118 of the stud out through the threaded aperture 116a of the sleeve 116. The dismounted but still connected position of the firing pin assembly is substantially that as shown in Fig. 4, except that, for economy of space in said figure, 50 the stud 117 and its supporting plate 120 are illustrated in the unexpanded position of the rear spring portion 123.

55 The rear of the receiver is closed by a removable receiver cap 125, previously mentioned. This receiver cap comprises a plate-like member having a down-turned rear wall 126 which affords a rear sight base 126a. The receiver cap also includes side walls, one of which is seen at 121 in Fig. 1. The front end of the receiver cap is 60 received beneath the rear edge of the bridge portion 68 of the receiver, Figs. 1 and 2. At the base of the back wall 126 of the receiver cap is a rearwardly fastened shoulder or ledge 130 adapted to seat beneath upstanding hook members 131 rising from the frame 135 of the trigger mechanism. Along the top face of the receiver cap 125 is a 65 T-shaped spring-metal retaining member 132 removably held in position beneath opposed overhanging ribs 133 on the receiver side walls. In 70 the closed position of the receiver cap, the front end of retaining member 132 abuts the bridge portion 68 of the receiver, and a foot 132a at the rear end of said retaining member is received in an appropriate recess 125a on the receiver cap. 75

In assembling, the front edge of the receiver cap is inserted beneath the receiver bridge 68. The cap is swung down in a pivotal manner, while presenting it forwardly against the spring seat or plate 120 and the firing pin springs, thus moving said seat or plate 120 slightly forwardly. The shoulder 130 on the rear wall 126 of the cap is brought below the stationary hooks 131 of the trigger frame. Release of the forward pressure on the cap permits the plate 120 to return rearwardly, completing engagement of said shoulder 130 of the cap and said hooks 131. At the same time the T-shaped spring member 132 at the top of the cap rides down off the receiver bridge 68, 15 into abutting position behind the latter, thus preventing forward movement of the cap and securely anchoring it in closed position. Removal of the receiver cap is readily effected by a reverse procedure, the front of the retaining member 132 being first lifted from behind the receiver bridge 68, and the receiver cap being pushed forwardly, by pressure on its rear wall 126, against the pressure of the firing pin springs 123, 114, to disengage the shoulder 130 and hooks 131. Thus it is seen that the firing pin springs and their rear seat or plate 120, through which rearward pressure is applied to the rear wall of the receiver cap, have the additional function of assisting to retain the latter in closed position. 20 On opening or removal of the receiver cap the firing pin assembly is readily removable, by disengaging the plate 120 from the receiver portion 2a. The entire breech closure unit, including the block 60, is then also bodily removable from the receiver, leaving the receiver and barrel exposed at the rear in direct prolongation of the axis of the bore.

My invention is not limited to the particular embodiment thereof herein shown and described, its scope being pointed out in the following claims.

I claim:

1. In a gun of the class described, a reciprocable breech block, a firing pin longitudinally movable in the block and having a longitudinal bore, and a firing pin actuating assembly comprising an elongated stud having its rear end mountable in the receiver, a sleeve longitudinally movably surrounding the stud, interengageable

means on the stud and sleeve preventing their unintentional bodily disengagement while permitting their relative longitudinal movement, an external collar on the sleeve, and a two-part coil spring received about the sleeve, at opposite sides of the collar, said stud, sleeve and spring being receivable in the bore of the firing pin. 5

2. In a gun of the class described, a reciprocable breech block, a firing pin longitudinally movable in the breech block and having a longitudinal bore, and a firing pin actuating assembly comprising an elongated stud, an elongated sleeve movably surrounding the stud, a coil spring received on the sleeve, said stud, sleeve and spring being receivable in the bore of the firing pin, 10 and a supporting element for the rear end of the stud removably held in fixed position on the receiver against the pressure of said spring. 15

3. In a gun of the class described, in combination, a receiver, a breech block reciprocable in 20 the receiver, to closed and to open positions, block locking means, a reciprocating actuator for the block and its locking means, a firing pin longitudinally movable in the block, a laterally extending head portion on the rear portion of the 25 firing pin and external of the block, and a projection on the actuator engageable with said head portion of the firing pin to retract the firing pin with respect to the block in connection with the block unlocking and opening movement of 30 the actuator.

4. In a gun of the class described, a reciprocable breech block, a firing pin longitudinally movable in the breech block and having a longitudinal bore, and a firing pin actuating assembly 35 comprising an elongated stud, an elongated sleeve movably surrounding the stud, a coil spring received on the sleeve, said stud, sleeve and spring being receivable in the bore of the firing pin, and a supporting element for the rear end of the 40 stud, said element comprising a main portion movably seated and guided on a fixed portion of the receiver, means normally limiting the movement of said element by engagement with the receiver but disengageable to free said element, and an operating portion for so disengaging said element. 45

JOSEPH C. WHITE.
